[57] CLAIM

The ornamental design for a eye glass stand, as shown
and described.

DESCRIPTION

FIG. 1 is a perspective view of the eye glass stand;
FIG. 2 is a side elevational view of the eye glass stand
shown in FIG. 1, the other side elevational view being
identical thereto;
FIG. 3 is a front elevational view of the eye glass stand;
FIG. 4 is a rear elevational view of the eye glass stand;
FIG. 5 is a top plan view of the eye glass stand; and,
FIG. 6 is a bottom plan view of the eye glass stand.

FIG. 1

FIG. 2

FIG. 3

FIG. 4

FIG. 5

FIG. 6
